UNITED STATES PATENT OFFICE

EMERY L. WALKER, OF WAUWATOSA, WISCONSIN, ASSIGNOR TO KIECKHEFER CONTAINER CO., OF MILWAUKEE, WISCONSIN, A CORPORATION OF MAINE

SEALING MACHINE FOR BOXES

Application filed August 24, 1927. Serial No. 215,251.

This invention relates to improvements in sealing machines for boxes.

A number of commodities are now shipped in paper, cardboard, fiber or corrugated boxes or containers and it is customary to seal the box cover to the box body by gummed paper or the like. Due to the fact that the cover has the tendency of bulging or springing from the sides and ends of the body, it must be firmly held thereagainst during the application of the gummed sealing strips and until the gum has dried and the strips adhered. Formerly, the sides and ends of the cover were manually held in place while the adhesive strips were applied and several persons were required for this operation.

It is, therefore, the primary object of the present invention to provide a machine which eliminates the above objections by firmly mechanically clamping the cover of a box against the body portion and so holding it for any desired period while gummed sealing strips are applied and adhered.

A further object of the invention is to provide a box sealing machine which will accommodate boxes of various sizes.

A further object of the invention is to provide a box sealing machine having two pairs of cover clamping arms which are operated simultaneously by two systems of equalizing levers, said equalizing levers being controlled by an operating lever which may be locked in any position of adjustment.

A further object of the invention is to provide a box sealing machine arranged so that boxes may be delivered thereto and removed therefrom by a conveyor.

A further object of the invention is to provide a box sealing machine which is simple in construction and operation, is strong and durable, and is well adapted for the purposes described.

With the above and other objects in view the invention consists of the improved box sealing machine, and its parts and combinations as set forth in the claims, and all equivalents thereof.

In the accompanying drawings in which the same reference characters indicate the same parts in all of the views;

Fig. 1 is a plan view of the improved box sealing machine;

Fig. 2 is a side view thereof indicated on line 2—2 of Fig. 1;

Fig. 3 is a vertical sectional view taken on line 3—3 of Fig. 1; and

Fig. 4 is an inverted plan view indicated on line 4—4 of Fig. 2.

Referring now more particularly to the drawings it will be seen that the machine includes a table 8 having an elevated horizontal top 9 supported by legs 10. Mounted on the top 9 is a track or conveyor 11, comprising a pair of spaced longitudinally extending angle iron members 12 bolted to the table top 60 and having journaled therein the end portions of transverse rollers 13, the rollers being of a diameter so as to project slightly above the top edges of the angle iron members 12. Also, the rollers are arranged in groups, 70 a central group over the mid-portion of the table top, and a group at each end thereof.

The table top 9 is provided with a pair of opposed end longitudinal slots 14, between the groups of rollers, and a pair of opposed side transverse slots 15. Extended through each slot 14 is a box end clamping arm 16 having a transverse engaging head portion 17, while a similar box side clamping arm 18 is extended through each slot 15, each arm 18 80 having a transverse engaging head portion 19.

The end clamping arms 16 are formed of two adjacent members 16' and 16'', the members 16'' being guide members and pivotally connected at their lower end portions to brackets 20 extending from the lower portions of the table. Also, the members 16'' are provided with projecting guide bolts 21 extended through slots 22 in the members 16', 90 the members 16' being, therefore, longitudinally slidable with respect to the members 16'' and pivotal therewith. The head portions 17 of the clamping arms 16 are fixed to the slidable members 16'.

The means for causing the arm members 16' to be moved longitudinally on the guide members 16'' comprise a lever 23 pivotally mounted at its inner end portion on a rod 24 mounted lengthwise in the lower portion of the 100

table. Said lever extends outwardly from a side of the table and is formed at its outer end portion with a foot pedal portion 25. The intermediate portion of a chain 26 is secured to an outer portion of the lever 23 and each end portion of the chain is secured to a lug 27 projecting from a lower portion of a 5 slideable arm member 16'. Intermediate portions of the chain extend over pulleys 28. 10 The normal position of the arms 16 is as shown in Fig. 3 with the head portions 17 below the upper level of the rollers 13 so as not to interfere with a box moved along the conveyor or tracks. However, if the foot pedal 15 25 is depressed, the chain 26 will be pulled and the arm members 16' will be longitudinally moved and raised on the guide members 16'' and will be projected above the track, as shown in dotted lines in Fig. 2. 20 Each of the arms 18 is pivotally connected at its lower end portion to a bracket 29 extending from the lower portion of the table. The normal position of said arms is as illustrated in Figs. 1 and 3, the head portions 19 25 being above the top of the angle members 12 and at the sides thereof, not interfering, when in this position, with the passage of a box along the track over the rollers.

Extended transversely through the lower 30 portion of the table is a revolvably mounted rod 30 and keyed to one end portion thereof, adjacent the foot pedal 25, is the lower end portion of an upwardly extending operating lever 31. A lever 32 is also mounted fast 35 on an intermediate portion of the rod 30 and pivotally secured to the bifurcated upper end portion 32' of the lever 32 is one end portion of a link 33. Pivotally secured to the other end portion of the link 33 is a link 34 and also 40 an arc shaped link 35. A pivot bolt 36 depends centrally from the table top and loosely centrally mounted thereon and retained by a nut 37 is a straight lever 38 and a bifurcated or forked lever 39. An end portion of the 45 link 34 is pivotally connected to one end portion of the straight lever 38 and also at said point of pivotal connection is one end portion of an arm 40. The other end portion of the arm 40 is pivotally connected, as at 41, 50 with an end clamping arm 16. The other end portion of the straight lever 38 has pivotally connected thereto an arm 42, similar to the arm 40, and said arm 42 is pivotally connected, as at 43, with the other end portion of the clamping arm 16.

One end portion of the forked lever 39 has pivotally connected thereto an arm 44 which extends to one of the side clamping arms 18 60 and is pivotally connected thereto, as at 45 and the opposite end portion of the lever 39 has pivotally connected thereto a similar arm 46 which extends to and is pivotally connected to, as at 47, the other side clamping arm 18. 65 The end of the forked portion 39' of the lever

39 is pivotally connected with members 33 and 34 by the curved link 35.

The arms, links and levers just described constitute two systems of equalizing levers for operating simultaneously the box end and side clamping arms. When the operating lever 31 is pulled to the right in Fig. 2, toward the dotted line position, the rod 30 will be turned and the lever 32 will likewise be moved toward the right. This movement will pull the arm 33 toward the right and through the levers 38 and 39 and connecting links 34 and 35, both pairs of arms 40, 42, and 44, 46, will be drawn inwardly, thereby moving the upper engaging portions of the pairs of clamping arms 16 and 18 inwardly. By reference to Figs. 1 and 2 it will be seen that the operating lever 31 is provided with a yieldable locking plate 48 and the side of the table along which the lever 31 moves has secured thereto a serrated member 49 so that the lever 31 may be releasably locked in any adjusted clamping position by the engagement of the plate 48 with any of the notches of the member 49.

In use, a box to be sealed is delivered upside down onto the angled members 12 and is pushed over the rollers to the central group of rollers 13, it being remembered that the arms 16 are normally in a lowered position so as not to interfere. When the box is thus positioned, as indicated at 50 in Fig. 2, the operator steps on the foot pedal 25 and depresses it. Through the lever 23 and chain 26 the arm members 16' are raised as previously described. Then, the operating lever 31 is moved to the right in Fig. 2 and through the systems of equalizing levers described the arms 16 and 18 are moved until their head portions firmly engage the sides and ends of the cover of the box, as shown in Fig. 2. The lever 31 is then locked to hold the arms in this position and gummed strips may be readily applied to the box to seal the cover to the body.

From the foregoing description it will be seen that the improved box sealing machine is of simple and novel construction, and is well adapted for the purpose set forth.

What I claim as my invention is:

1. A box sealing machine, comprising a base member, a pair of opposed clamping members mounted therein and movable upwardly and longitudinally of the base member, a second pair of opposed clamping members mounted in the base member and movable transversely thereof, and means for jointly pivotally moving said clamping members toward a central point.

2. A box sealing machine, comprising a base member having a longitudinal conveyor of which a portion serves as a box supporting portion, two pairs of opposed clamping arms mounted in said base member and movable toward the edges of said box support-

ing portion, there also being a relative vertical movement between the pair of clamping arms positioned longitudinally of the conveyor and the latter, and connected means for jointly moving both pairs of arms toward said conveyor portion serving as a box supporting portion.

3. A box sealing machine, comprising a base member having a box conveyor of which a portion serves as a box supporting portion, a pair of opposed end clamping arms movable longitudinally of the conveyor toward each other, a pair of opposed side clamping arms movable transversely of the conveyor toward each other, means for moving the end clamping arms from a position below the top of the conveyor upwardly, and means for jointly operating said pairs of arms to move the arms of each pair toward each other.

20 4. A box sealing machine, comprising a base member having a box supporting portion, a pair of opposed end clamping arms movable longitudinally of the base member toward each other, a pair of opposed side clamping arms movable transversely of the base member toward each other, there being a relative vertical movement between the end clamping arms and the box supporting portion, means for causing the relative vertical movement between said pair of arms and the box supporting portion, and other means for jointly operating said pairs of arms to move the arms of each pair toward each other.

35 5. A box sealing machine, comprising a base member, a track mounted thereon and having a station portion centrally of the base member, a pair of opposed end clamping arms movable longitudinally of the track toward each other, and normally in a lowered position below the level of said track, a pair of opposed side clamping arms movable transversely of the track toward each other, means for raising the end clamping arms, and other means for jointly operating said pairs of arms to move all of said arms inwardly toward the station portion.

6. A box sealing machine, comprising a base member, two pairs of opposed clamping arms pivotally mounted in said base member, the clamping portions of all of said arms being movable toward a central point, two sets of equalizing levers directly connected together and connecting all of said arms for moving the same simultaneously, and other means for jointly operating both sets of said levers.

7. A box sealing machine, comprising a base member, a track mounted thereon and having a station portion centrally of the base member, a pair of opposed end clamping arms pivotally mounted in the base member and movable longitudinally of the track member toward each other and normally in a lowered position below said track, a lever

connected with said arms for raising the same, a pair of opposed side clamping arms pivotally mounted in the base member and movable transversely of the track toward each other, two sets of equalizing levers connected together and connecting all of said arms for moving the same toward one another, lever means for jointly operating both sets of equalizing levers, and means for releasably locking said mechanism in arm engaging positions.

8. A box sealing machine, comprising a base member having a station portion, a pair of opposed end clamping arms movable longitudinally of the station portion toward each other, a pair of opposed side clamping arms movable transversely of the station portion toward each other, there being a relative vertical movement between the end clamping arms and the station portion and said end clamping arms being normally disposed below the level of said station portion, means for causing the relative vertical movement between said pair of arms and said station portion, other means for jointly operating said pairs of arms to move the arms of each pair toward each other, and means for releasably locking said arms in adjusted positions.

In testimony whereof, I affix my signature. 95
EMERY L. WALKER.
